UNITED STATES PATENT OFFICE.

EDGAR D. ALDRICH, OF PITTSFIELD, MASSACHUSETTS.

IMPROVEMENT IN SCYTHE-HOLDERS FOR RAG-CUTTERS.

Specification forming part of Letters Patent No. **145,475**, dated December 16, 1873; application filed May 7, 1873.

To all whom it may concern:

Be it known that I, EDGAR D. ALDRICH, of Pittsfield, Berkshire county, State of Massachusetts, have invented an Improved Scythe-Holder for Rag-Cutters, of which the following is a specification:

My invention consists of a device for holding the section of scythe-blade used to cut rags in paper-mills securely, and in such way that it can readily be detached to be ground or reversed, and can be tightened in place easily and quickly, and by mechanism arranged to be entirely out of the way of the operator, and that cannot catch in the rags.

In the drawings, Figures I, II, and III show different views of my invention.

The holder proper, B, is of cast metal, in one piece, and has a flat base to bear against the side of the table, to which it is attached by means of bolts passing through holes left in the flanges *b b*, as seen in Fig. I. The sides of the holder, which may be made as light as is consistent with strength, support the top C and bottom D, which afford the two bearings *d g* to the scythe-blade H. These openings *d g* in the top C and bottom D, I form of a triangular shape to conform to a cross-section of the blade H, and are relatively arranged to give the desired inclination to the blade when in place; and the blade H, when in bearings in the shell, is as firm as though seated in a solid block of the same thickness as the holder B. The scythe-blade H, when in place within the holder, is grasped by the bolt-hook L, the

screw-shank of which passes through the holder to the outside through the nut O, and the thumb-nut W enables the scythe-blade H to be tightened or released at will. As the greatest pressure is exerted upon the blade to remove it from its top bearing, the hook L is arranged, as shown in Fig. I, to grasp the scythe at a point nearer the bearing *d*.

In the holder in common use, in which the blade is held in a staple by wedges, and has the staple drawn against the table by a bolt passing through the latter to the front, the nut necessary to secure the end of the bolt interferes with the operator, and the wrench to loosen it has to be detached when not in use, and fragments of wooden wedges are liable to become mixed with the rags, and the wedges require frequent adjustment; but in my device all inconveniences are entirely done away with, and a broad flat surface forms a base to the cutting-edge of the blade, and is flush with the surface of the work-table.

Now having described my invention, what I claim is—

The scythe-holder, consisting of the flanged shell B, having the openings *d g* and nut O, in combination with the hook-bolt L and nut W, the parts being constructed and arranged substantially in the manner and for the purpose as set forth.

EDGAR D. ALDRICH.
